SOLDERLESS CONNECTOR TERMINAL
STRUCTURE

Charles L. Jones, Beaver, Pa., assignor to Westinghouse Electric Corporation, East Pittsburgh, Pa., a corporation of Pennsylvania

Application April 5, 1954, Serial No. 420,919

9 Claims. (Cl. 339—265)

My invention relates, generally, to terminal constructions for electrical equipment such as circuit interrupters and, more particularly, to connectors of the solderless type.

An object of my invention is to provide a connector which shall be suitable for connecting either one or a plurality of cables to a terminal.

Another object of my invention is to provide a connector capable of receiving cables of different sizes.

A further object of my invention is to provide a connector which may be installed in a relatively narrow space and requires much less space in the direction along the length of the circuit interrupter.

Still another object of my invention is to provide a connector having interlocking parts for preventing the strands of a stranded cable from being squeezed out of proper position and interfering with the tightening of the connector.

A still further object of my invention is to provide a connector having certain identical interchangeable parts to keep the tool and inventory expense low.

An additional object is to provide a terminal construction for a circuit breaker or other electrical device in which no live parts are exposed adjacent the end of the insulating housing of the circuit breaker.

Other objects of my invention will be explained fully hereinafter or will be apparent to those skilled in the art.

My invention provides several improvements over the two types of terminal constructions illustrated, for example, in Grissinger et al. Patent No. 2,435,305, issued February 3, 1948. One improvement resides in the fact that my novel terminal takes up much less space in the direction of the length of the circuit breaker and does not extend to a point close to the end of the insulating housing so that the live parts are protected from being accidentally touched either by a person who would be shocked or by a tool which could cause a short circuit. My connector is of the solderless type and has the further advantages that it is adjustable to receive a range of different size cables, and in addition can receive a plurality of cables rather than just one.

These improvements are obtained by providing two threaded inserts in the insulating base of the circuit interrupter. These are spaced apart as far as permitted by the relative narrow width between the insulating walls defining the pole space, so that the end of the cable may extend into the space between two studs threaded into the inserts and be clamped between grooved plates extending across the space between the studs. With this construction, no live parts extend out to the end of the insulating housing as have the solder lugs or solderless lugs used in the past.

In accordance with one embodiment of my invention, a connector comprises a plurality of clamping plates which are held together by two spaced stud bolts threaded into a terminal on a circuit breaker. Each plate is recessed around the hole for one bolt and has a projection around the hole for the other bolt. The recess and

2

the projection are so shaped that when a plate is reversed the projection on one end fits into the recess in an adjacent plate, thereby interlocking the two plates. The plates are preferably identical, thereby making them interchangeable. Each plate has a transverse groove therein for receiving a cable which is clamped between two plates.

For a better understanding of the nature and objects of the invention, reference may be had to the following 10 detailed description, taken in conjunction with the accompanying drawing, in which:

Figure 1 is a view, partly in section and partly in elevation, showing a connector embodying the principal features of my invention utilized for connecting cables to 15 the terminal of a circuit breaker, only a portion of which is shown;

Fig. 2 is another view, partly in section and partly in elevation of the structure shown in Fig. 1;

Fig. 3 is a view, in section, taken along the lines 20 III—III in Fig. 2, the connector plates being clamped closer together;

Fig. 4 is an enlarged view, in end elevation, of one of the connector plates;

Fig. 5 is an enlarged view, in plan, of the connector 25 plate;

Fig. 6 is a view, in section, taken along the line VI—VI in Fig. 5;

Fig. 7 is a view, in side elevation, of one of the stud 30 bolts for clamping the plates together, and

Fig. 8 is a view, in end elevation, of the bolt.

Referring to the drawing, and particularly to Figs. 1 and 2, the structure shown therein comprises an end portion of a circuit breaker casing having a base member 10 and a removable cover member 11. These casing 35 members may be composed of a suitable molded insulating material. Metal inserts 12 are molded or otherwise secured in the base member 10. As shown in Fig. 1, each insert 12 has a threaded hole therein for receiving the threaded end of a stud bolt 13. The holes in the 40 inserts extend all of the way through the inserts so that connection to a terminal conductor 14 may also be made from the rear of the base of the circuit interrupter. The terminal conductor 14 has one end resting on the inserts 12. The other end of the terminal conductor 14 may 45 be connected to a contact member of the circuit breaker (not shown).

In order to connect one or more cables to the terminal conductor 14, a connector comprising a plurality of clamping plates 15 is provided. As shown most clearly 50 in Fig. 5, each plate 15 has two spaced holes 16 and 17 extending through the plate. A recessed area 18 surrounds one of the holes 16. A raised area or projection 19 surrounds the other hole 17.

As shown in Fig. 4, the walls of the recessed area 18 55 have sloping surfaces 21 and the raised area 19 has surfaces 22 which slope oppositely from the surfaces 21. Thus, when two plates 15 are assembled in reversed relation the raised portion or projection 19 of one plate fits into the recessed area 18 of the other plate. In this manner the two plates are interlocked together when they 60 are assembled in reversed relation.

As also shown in Figs. 5 and 6, each plate 15 has a transverse groove 23 disposed between the holes 16 and 17. The groove 23 is generally semi-cylindrical. Thus, 65 when two plates are assembled in reverse relation a generally cylindrical opening is provided between the plates for receiving a cable 24.

As shown in Fig. 3, when a small or medium size cable 70 is utilized the edges of the grooves 23 overlap each other at 25, thereby preventing the strands of the cable 24 from being forced outside of the opening formed by the grooves 23 when pressure is applied on the cable by tightening nuts

26 on the bolts 13. As shown in Fig. 1, when relatively large cables 24 are utilized the plates do not quite overlap each other but the interlocked recesses and projections help to keep the strands properly bunched together when stranded cable is used. Thus, the connector functions satisfactorily with a relatively wide range of cable sizes having different current carrying capacities.

As shown in Figs. 1 and 2, four plates 15, which are identical in construction, may be assembled in the manner shown to connect two cables 24 to the terminal conductor 14. If it is desired to increase the number of cables, additional plates may be assembled in the manner shown by providing longer stud bolts 13 and increasing the size of the breaker casing.

As shown in Fig. 6, the side of the plate 15 opposite the recessed area 18 and the raised area 19 has a flat surface 27. The flat surfaces 27 of two plates engage when the two plates are disposed back-to-back as shown in Fig. 1. If desired, these two plates may be made as one piece having the recessed and raised portions on opposite sides of the plate.

Referring to Fig. 5, it will be seen that the hole 16 has a flat side 28 adjacent to the groove 23. Likewise, the hole 17 has a flat side 29 adjacent to the groove 23. Referring to Figs. 7 and 8, it will be seen that the bolt 13 has a flat side 31 similar to the flat sides in the holes 16 and 17. The flat sides in the holes 16 and 17 permit the bolts to be located relatively close to the sides of the groove 23 without interfering with the insertion of the cables in the openings in the connector.

In this manner bolts of sufficient size to have the desired strength may be utilized without increasing the length of the plates 15 and without decreasing the strength of the plates by providing holes of sufficient size to take relatively large bolts. As shown in Fig. 8, a slot 32 is provided in one end of each bolt 13 to permit a screwdriver to be utilized to thread a bolt into an insert 12.

Referring to Figs. 1 and 2, it will be seen that an assembled group of plates 15, of the type herein described, may be utilized to connect electrically two or more conductors by clamping the plates together in the manner shown by means of bolts inserted through the holes 16 and 17 to draw the plates together against the conductors. Thus, the connectors may be utilized as a means of splicing two or more conductors together.

One advantage of the connector is illustrated in Fig. 2 from which it is seen that the connector requires only a relative short space in the direction along the length of the cable. This permits the connector to be spaced back from the end of the enclosing housing to insure that no live conducting parts are accessible from the outside of the housing. As shown, the insulation need be stripped from only the ends of the cables that are to be positioned between the plates, and the insulated portion of the cables may extend into the housing so that no live parts are exposed to give one an electrical shock. This advantage is possible without greatly elongating the housing because the connector utilizes the full width available and clamps the conductors in the space between the two bolts.

From the foregoing description it is apparent that I have provided a connector which utilizes a plurality of plates which are so shaped that they are interlocked together when assembled in reversed relation, thereby retaining the plates in the assembled relation. The connector is suitable for connecting one or more cables to a terminal member. The number of cables may be increased or decreased by varying the number of plates utilized. Furthermore, cables of different sizes may be utilized with the connector. The connector may also be utilized for electrically connecting two or more cables together.

Since numerous changes may be made in the above-described construction, and different embodiments of the invention may be made without departing from the spirit and scope thereof, it is intended that all matter contained

in the foregoing description or shown in the accompanying drawing shall be interpreted as illustrative and not in a limiting sense.

I claim as my invention:

- 5 1. A connector for electrically connecting two or more conductors comprising, a plurality of plates having two spaced holes therethrough, each plate having a recessed area around one hole and a raised area around the other hole, said areas having side walls which slope in opposite directions, said areas being on the same side of said plate, the opposite side of said plate being substantially flat, said raised area on one plate fitting into the recessed area in another plate with said walls engaging each other when said plates are assembled in reversed relation, the flat sides of at least two of said plates engaging when the plates are assembled, each plate having a transverse groove therein between said holes, said grooves forming openings between said plates for the conductors when the plates are assembled in reversed relation, and bolts disposed in said holes for clamping the plates against the conductors.
- 10 2. A connector for connecting a conductor to a terminal, said connector comprising a plurality of plates having two spaced holes therethrough, each plate having a recessed area adjacent one hole and a raised area adjacent the other hole, said raised area on one plate fitting into the recessed area in another plate when said plates are assembled, each plate having a transverse groove therein between said holes, said grooves forming an opening between said plates for the conductor, a terminal member, bolts extending through said holes and the terminal member to clamp said plates against the conductor, each hole having a flat side adjacent to the groove in each plate, and each bolt having a flat side corresponding to the flat side in a hole.
- 15 3. A connector for electrically connecting two conductors comprising, a plurality of plates having two spaced holes therethrough, each plate having a recessed area around one hole and a raised area around the other hole, said raised area on one plate fitting into the recessed area in another plate when said plates are assembled, each plate having a transverse groove therein between said holes, said grooves forming openings between said plates for the conductors when the plates are assembled in reversed relation, bolts disposed in said holes for clamping the plates against the conductor, each hole having a flat side adjacent to the groove in each plate, and each bolt having a flat side similar to the flat side in a hole.
- 20 4. A connector for connecting a conductor to a terminal, said connector comprising a plurality of plates having two spaced holes therethrough, each plate having a recessed area around one hole and a raised area around the other hole, said raised area on one plate fitting into the recessed area in another plate when said plates are assembled, each plate having a transverse groove therein between said holes, the edges of said grooves overlapping to form an opening having closed sides between said plates for the conductor, a terminal member, bolts extending through said holes and the terminal member to clamp said plates against the conductor, each hole having a flat side adjacent to the groove in each plate, and each bolt having a flat side corresponding to the flat side in a hole.
- 25 5. A connector for electrically connecting two conductors comprising, at least three plates each having two spaced holes therethrough, one side of each of two outer plates having a recessed area around one hole and a raised area around the other hole, opposite sides of an intermediate plate having a recessed area around one hole and a raised area around the other hole, said raised area on one plate fitting into the recessed area in another plate when said plates are assembled, each outer plate having a transverse groove therein on one side between said holes, the intermediate plate having a transverse groove therein on opposite sides between said holes, the edges of the grooves in adjacent plates overlapping to form an

opening having closed sides between said plates for a conductor, bolts disposed in said holes for clamping the plates against the conductors, each hole having a flat side adjacent to the groove in each plate, and each bolt having a flat side corresponding to the flat side in a hole.

6. An electrical device having a base and cover of insulating material, a pair of inserts extending through the base, said inserts being spaced apart from each other and being spaced inwardly from the end of the base and cover, a threaded hole extending through each of said inserts, a terminal conductor on the upper side of the base and having its outer end positioned on top of the two inserts, a pair of holes through said terminal conductor, each of said holes being in alignment with one of the holes in one of the inserts, a pair of threaded studs extending into said inserts, one or more conducting members each having two holes therethrough positioned on and extending between said pair of studs, and a groove in one or more of said conducting members between said studs for clamping the end portion of a cable.

7. An electrical device having a base and cover of insulating material, a pair of inserts extending through the base, said inserts being spaced apart from each other and being spaced inwardly from the end of the base and cover, a threaded hole extending through each of said inserts, a terminal conductor on the upper side of the base and having its outer end positioned on top of the two inserts, a pair of holes through said terminal conductor, each of said holes being in alignment with one of the holes in one of the inserts, a plurality of plates having two spaced holes therethrough, each plate having a recessed area adjacent one hole and a raised area adjacent the other hole, said raised area on one plate fitting into the recessed area in another plate when said plates are assembled, each plate having a transverse groove therein between said holes, said grooves forming an opening between said plates for the cable, and bolts extending through said holes and the terminal conductor to clamp said plates against the conductor, and against the pair of inserts.

8. An electrical device having a base of insulating material, opening means extending through the base, said opening means being spaced inwardly from the end of the base, a terminal conductor on the upper side of the base and having its outer end positioned on top of the opening means, a pair of holes through said terminal

conductor, each of said holes being over part of said opening means through the base, a plurality of plates having two spaced holes therethrough, each plate having a transverse groove therein between said holes, said grooves forming an opening between said plates for a cable, bolts extending through said holes and the terminal conductor to clamp said plates against the conductor and the cable, each hole having a flat side adjacent to the groove in each plate, and each bolt having a flat side corresponding to the flat side in a hole.

9. An electrical device having an elongated base of insulating material, opening means extending through the base, said opening means being spaced inwardly from the end of the base, a terminal conductor on the upper side of the base, said conductor having a flat surface at its outer end positioned over the opening means, a pair of holes through said terminal conductor, said holes being spaced apart from each other transversely of the base, each of said holes being over part of said opening means through the base, at least two pairs of identical conducting members, each of said members having two holes therethrough, each of said holes in the conducting members being in alignment with one of the holes in the terminal conductor, each conducting member being of substantially the same width as the terminal conductor, each conducting member having a flat surface on one side and a transverse groove in the side opposite the flat surface and between said holes, said grooves forming openings between said conducting members for cables when said members are assembled in reversed relation with the flat surface of one member engaging the flat surface of the terminal conductor and the flat surfaces of two of said members engaging each other, and bolts extending through said holes and the terminal conductor to clamp the conducting members to the conductor.
